UNITED STATES PATENT OFFICE.

JAMES J. OGILVIE, OF ROSCOE, OHIO.

FENCE-POST.

SPECIFICATION forming part of Letters Patent No. 325,357, dated September 1, 1895.

Application filed March 27, 1895. (No model.)

To all whom it may concern:

Be it known that I, JAMES J. OGILVIE, a citizen of the United States, residing at Roscoe, in the county of Coshocton and State of Ohio, have invented certain new and useful Improvements in Fence-Posts; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to an improvement in fence-posts; and it consists in a fence-post constructed of two thin sections of wood so arranged that the edge of one section shall abut against the middle of the other, and the grain 20 or fiber of one of the sections shall be at right angles to the other one to prevent springing or bending, the two sections being connected by metallic pins passing through both sections, and each end of such pins projecting 25 from the sections, and the post being encircled with wires which are wound around the extremities of the pins, where they project on each side.

The object of my invention is to produce a 30 post which may be made of plank or thin sections of split wood, and which combines all the strength of a solid post, but is lighter than such, and can be more readily and cheaply produced.

35 In many parts of the country, notably in the region west of the Missouri river, it is difficult to obtain timber large enough to dress into solid posts, and the cost of its transportation from other localities is very great; but by my 40 device posts may be made of plank one inch or more in thickness, and the same material of which the rails are made will answer to construct the posts.

In the accompanying drawings, Figure 1 is 45 a front perspective view of my post. Fig. 2 is a rear view of the same. Fig. 3 is a section on the line of one of the connecting pins and wires; and Fig. 4 is an illustration of a modification of my device.

50 I construct my post of a front section, A, of wood, say six inches wide and one and a half

inch thick, and of suitable length to allow of being sunk in the earth the requisite depth, and leave sufficient height above the ground to attach the rails. At a point a little above 55 the ground I make an opening, a, in the center of the section A, and a similar opening, a', near the top of the section. Another section, P, of like dimensions, having openings a and a' through its edge or greater thickness, is then 60 placed longitudinally against the rear of section A, the edge of section B resting on the center of the broad side of section A and the openings a a' in each corresponding. I then pass or drive through the openings a a' in each 65 section, the two metal pins or bolts C, which are slightly larger than the openings, until their extremities are left projecting a little beyond the front side of section A and the rear edge of section B, respectively. I then twist 70 a wire, D, in a loop around the projecting end of the pin C which passes beyond section B, and wind the wire once around sections B and A, and twist the same around the head or end of the pin C which projects in front of section 75 A, so that by the pins C and the wires D the two sections A and B will be securely bound and firmly held together and form the post.

Where plank is used in constructing the 80 panels of the fence, it will be nailed to the front face of section A, and the nails will be driven through into the edge of section B, thus securing a good body for nail-hold and further binding the sections together. When the post is used for wire fencing, the wire can 85 be attached by pins driven in section A, or by winding around the whole post, or in any usual way.

Another advantage of my post is that should 90 one of the sections decay it can be removed and replaced by unwinding the wires and withdrawing the pins from the sections without destroying the other section.

In Fig. 4 my post is provided with a series of mortises or rests, E E, in the front edge of 95 section B, before the posts are connected to receive the ends of planks or rails, which with the posts constitute what is commonly denominated a "post-and-rail fence."

I do not desire to claim a fence-panel, but 100 simply a post constructed of two pieces of thin wood connected by two metal pins and

bound together by encircling wires, one of the pieces or sections having its edge longitudinally abutting against the center of the flat side of the other to economize material, 5 and to gain the maximum of strength with the minimum of weight. A single strip of wood of the dimensions of section A would bend or spring if used for a post; but two pieces with their edges at right angles, as in 10 my device, have all the firmness of a solid post six inches square.

I am aware that battens have hitherto been used on fence-posts for the purpose of re-enforcing and strengthening them, and I do not 15 claim such devices; but

What I do claim as my invention, and desire to secure by Letters Patent, is—

1. A fence-post formed of a wooden strip, A, and a second wooden strip, B, of equal dimensions, said strips or sections being placed 20 at right angles to each other to prevent bend-

ing or yielding, and the section B having a series of mortises, E, cut therein to receive the rails, and connected by metallic pins C, and bound by encircling wires wound around the sections A and B and the projecting ends of the pins C, substantially as set forth. 25

2. A fence-post formed of two thin sections of wood placed at right angles to each other, and bolted together by two metal pins whose ends project to form catches for encircling-wires, said wires being wrapped around the wooden sections which form the post, and also around the projecting ends of the pins, all substantially as shown and described. 30

In testimony whereof I affix my signature in presence of two witnesses.

JAMES J. OGILVIE.
